UNITED STATES PATENT OFFICE.

GARTH GRIFFITH GILPIN, OF RIVERSIDE, ILLINOIS, ASSIGNOR TO WALTER P. MURPHY, OF CHICAGO, ILLINOIS.

UNCOUPLING-LEVER FOR CAR-COUPINGS.

1,181,953.

Specification of Letters Patent.

Patented May 2, 1916.

Original application filed April 24, 1912, Serial No. 692,837. Renewed November 7, 1915, Serial No. 60,419. Divided and this application filed December 22, 1915. Serial No. 68,211.

To all whom it may concern:

Be it known that I, GARTH GRIFFITH GILPIN, a citizen of the United States, residing at Riverside, in the county of Cook and 5 State of Illinois, have invented certain new and useful Improvements in Uncoupling Levers for Car-Couplings, of which the following is a specification.

One of the principal objects of my invention 10 is to provide a device of novel construction in which a rigid link is utilized for lifting the locking pin of the coupler, this link being directly connected with the vertically 15 lifting locking pin of the coupler and with the operating member of the uncoupling device by connections which allow the coupler perfect freedom in its normal intended 20 movements, both lateral and longitudinal, and which furthermore permits an easy, free, and unimpeded manipulation of the 25 device during the operation of raising the locking pin.

A further object of my invention is to do away with clevises, bolts, pins, and other 25 parts of like character which are apt to be injured or which may be lost when an uncoupling device comprising such parts is detached from the coupling for the purpose, for example, of repairing the latter.

30 A further object is to provide a device of the general character herein shown which will operate to automatically raise the locking pin upon an abnormal forward movement of the coupler due to the failure of the 35 coupler or some of its connections.

This application is filed as a division of my application filed April 24, 1912, Serial No. 692,837.

In the drawings: Figure 1 is an end elevation of a car, broken away, with my uncoupling lever in position thereon. Fig. 2 is a top plan view of Fig. 1. Fig. 3 is an end elevation of Fig. 1. Fig. 4 is a front elevation of the rigid link. Fig. 5 is a side 45 elevation of the rigid link. Fig. 6 is a detail view showing, in dotted lines, positions which the link will assume when the coupler moves laterally. Fig. 7 is a detail view showing, in dotted lines, positions which 50 the link will assume when the coupler moves longitudinally under buff and draft strains.

The reference character 1 designates a car, 2 a coupler, which may be of any im-

proved M. C. B. construction which is resiliently mounted on a car. 55

A center bracket 3 is mounted substantially at the center of the end of the car and, as shown in the drawing, is secured to the deadwood 4 and is provided with an enlarged opening 5 constituting a bearing for 60 the inner end of the operating rod 6. A bracket 7 is secured to the end of the car near one side thereof and is provided with an opening which constitutes a bearing for 65 the outer end portion of the operating rod 6.

The operating rod 6 is provided with a depending handle 8 at its outer end which is adapted to lie normally close to the end structure of the car; the inner end of the operating rod terminates in a crank or lever 70 9, which extends forwardly from the end of the car to a point substantially over the coupler and is provided with an eye 10 at its outer end extending in a horizontal plane as shown and is positioned, when the parts are 75 at rest, substantially in the vertical plane of the coupler or locking pin 11, which is provided with an eye at its upper end.

A single rigid link 12 which constitutes the connection between the locking pin 11 of 80 the coupler and the operating rod 6 is provided at its lower end with an open hook 13, the end portion 14 of which is deflected from the plane of the link and the rest of the hook, the upper portion of the link extending 85 and vertically slidably through the eye 10 of the crank 9 of the operating rod, and provided preferably with a substantially ball shaped end 14^a, which, with the eye 10 constitutes, in a measure, a ball and socket joint 90 between the rigid link 12 and the crank of the operating rod, although the ball 14 is not confined to its socket against upward movement relative thereto, but is free to permit the rigid link to adapt itself to all normal 95 service movements of the coupler without imposing strain upon any of the parts.

The deflection of the portion 14 of the open hook 13 from the plane of the hook and the rest of the link is relative, and the open space of the hook may be more or less as may be found necessary in service conditions, the object being to provide a more or less (in effect) spiral portion in the hook which will prevent the hook from becoming 100 105 disengaged from the lock pin by service

movements. In other words the rigid link must be given an axial movement to disengage its hook from the lock pin.

While I have shown my invention in a typical embodiment it will be understood that modifications might be made without departure from the principles of the invention as defined by the claims herein.

What I claim is:

- 10 1. In a release rigging for a car coupler having a lock pin, said rigging including an operating rod having a crank, a rigid link provided with a spiral hook at its lower end for connecting said link with the lock pin of the coupler, and a flexible connection between the upper end of the said link and the said crank, whereby the link may move vertically relatively to said crank and rotate about its longitudinal axis to permit 15 the engagement and disengagement of said link with said lock pin.
- 20 2. The combination with a railway car and a coupler resiliently supported on the car and provided with a lock pin adapted to be raised to its unlocking position and formed with an eye; of a release rigging comprising a rod revolvably supported on the car, provided with a crank, and a rigid member extending from said crank to the 25 lock pin, the upper end of which is connected with the crank slidably, in the direc- 30

tion of its length, and also flexibly to permit angular movements of said member both forward and back and sidewise, the lower end being provided with an open substantially spirally shaped hook adapted to engage the eye of the lock pin. 35

3. In combination, a car, a coupler resiliently mounted on the car and having a lock pin which is raised to unlock the same and a release rigging comprising a link having a substantially spiral hook on one end loosely engaging said lock pin, and an operating rod having a crank provided with means formed with an aperture through which 40 said link extends loosely and slidably, the link being formed with an enlarged rounded head to maintain a flexible engagement between it and the crank. 45

4. In combination a car, a resiliently sustained coupler on the car having a lock pin, and a release rigging comprising a rod revolvably mounted on the car and formed with a crank provided with an eye, a rigid link slideable vertically through said eye and provided at its lower end with a hook 50 adapted to extend through the eye of the lock pin transversely of the coupler with its extremity deflected from the plane of the rest of the hook. 55

GARTH GRIFFITH GILPIN.
